UNITED STATES PATENT OFFICE.

AUGUST JACOB VENTZKI, OF GRAUDENZ, PRUSSIA, GERMANY.

PLOW.

SPECIFICATION forming part of Letters Patent No. 408,331, dated August 6, 1889.

Application filed April 2, 1888. Renewed June 25, 1889. Serial No. 315,509. (No model.)

To all whom it may concern:

Be it known that I, AUGUST JACOB VENTZKI, a subject of the King of Prussia, German Emperor, and a resident in the city of Graudenz, 5 in the Kingdom of Prussia, Germany, have invented certain new and useful Improvements in Plows, of which the following is a full, clear, and exact specification.

This invention relates to plows which can 10 be made to work either with one share or with two or more shares, and is distinguished from other implements of a like nature by the facility with which the furrow and the supporting-wheels can be shifted by means of a lever, and also by a device for applying the 15 pull at any required point, so that the plow can always be drawn in a straight line.

In the drawings which form a part of this 20 specification, Figure 1 is a side elevation of the plow in position for working; Fig. 2, a side elevation of the plow in a position ready for transport; Fig. 3, a plan; Figs. 4 to 7, details of the plow.

The main frame R, Figs. 1 to 3, rests on the 25 bearings of the bent axles a a' , on which the furrow-wheel F and the supporting-wheel L are respectively mounted. These two axles are so moved by the lever W that the axle a of the supporting-wheel is moved a greater 30 distance than the axle a' , and the depth of the furrows determined by the difference of the positions of the front wheels.

Both arms s and s' of the lever W, which move the two axles by means of the connecting-rods S and S', the latter being connected with the axle a' through the medium of arm h' , are so situated that the arm s' is at the dead-point when the furrow-wheel has attained its proper position—that is to say, the 40 horizontal plane of the sole of the plowshare. Now, as in this position, Fig. 1, the motion of the furrow-wheel is very small, owing to the arm s' being in the neighborhood of the dead-point, and as at the same time the motion 45 of the arm s , connected to the axle of the supporting-wheel, is at its maximum, an alteration in the height of the wheels in respect to each other is the result, and the depth of the furrows is determined by simply moving the lever W.

The axle a' of the furrow-wheel is capable of sliding in the guiding-blocks f and in the

regulating-ring h . This contrivance allows the distance between the furrow-wheel and the supporting-wheel to be increased, so that a plow with one share can be provided with two shares, if desired. (See dotted lines, Figs. 1 and 3.) In this case the right-hand wheel is shifted (see dotted lines) so as to travel in the furrow without coming out of engagement 60 with the lever mechanism. The wheel F could, if desired, be shifted on the axle, (instead of the axle being moved,) in order to alter the distance apart of the wheels, in which case the straight part on which the wheel is 65 mounted is made longer.

Both connecting-rods S and S', which transmit the motion of the hand-lever W to the axles, are divided in the middle, (see Figs. 4 and 5,) and the length of these two parts can 70 be adjusted by means of bolts i and i' in the following manner: In one half there is an elongated hole or slot, in which the bolts can be made to slide. By tightening the bolt the projection n on the one half of the connecting-rod 75 engages one of the notches made on the other half. In this manner both ends of the connecting-rod can be joined together, so as to be capable of being adjusted.

The draft-bar z , Fig. 6, made, preferably, of 80 T-iron, is arranged so as to be capable of adjustment on the cross-piece of the framing by means of the claw k and adjusting-bolt e . At the rear end the draft-bar can be fixed by means of bolts or pins inserted through one 85 of the holes of the arm Z and the rack. In consequence of this arrangement it is possible to fix the draw-gear in any required position, no matter what is the space between the wheels. It can be shifted to the right or to 90 the left, up or down, forward or backward, parallel or diagonally to the main framing. If, for instance, three horses are employed for cutting more than one furrow, the traction-line is on the left toward the outside of the main 95 framing, and the draft-bar z must be placed diagonally, (the dotted lines in Fig. 3 show this position,) as otherwise the horses would draw the share toward the side of the land, and thereby make the furrows broader and 100 broader. On the contrary, when the draft-bar is placed in a diagonal position, the plowshare will be drawn exactly in the direction of the furrows. By means of this draw-gear the

plow is drawn along in a straight line with a loose chain, whose point of application is within the limits of the frame. The plow is by this arrangement drawn along safely not only in plowing and turning up flat land with one or more plowshares, but also hilly surfaces. The turning of the plow is also rendered more easy by the use of this draw-gear.

Having now particularly described and ascertained the nature of the said invention and in what manner the same is to be performed, I declare that what I claim is—

1. In a plow, the axles a a' , forming knees for the two fore wheels L F , which can be moved by an angle-lever W , provided with two arms, by means of adjustable driving-rodS S S' , so that the different large adjustments of the two wheels enable the determination of the depth of the furrow, whereby the arm of the angle-lever which places the furrow-wheel in position stands on the dead-point as soon as the wheel has obtained its correct position, in order to enable the placing and displacing of the plow by means of one single lever.

2. The combination, in a plow, of the axle a' , adjustable in the direction of its length, and the axle a of the furrow-wheel, for the purpose of changing the distance of the two fore wheels as may be necessary, and a frame adapted to carry one or two plows, and thus

to transform a one-shared plow into a two-shared plow in such manner that the furrow-wheel can in each case be placed in the last furrow and can be kept by this in its correct position.

3. In a plow such as described, the combination, with the furrow-wheel F , the bearings f , the regulating-ring h , and the arm h' , of an axle a' , which is capable of being adjusted in the direction of its length within said bearings and ring, for the purpose of using the plow as a single or double share plow, in such a manner that in both modes of working the furrow-wheel can always be placed in the furrow last made, so as to be guided by it, substantially as set forth.

4. In a plow such as described, the connecting-rodS S S' , which can be adjusted as regards their length and made to transmit the motion of the lever W to the axles a a' , for the purpose of adjusting the position of the wheels with respect to each other, in combination with said lever and its differently-located arms s s' , substantially as set forth.

In testimony whereof I have signed my name to this specification in the presence of two subscribing witnesses.

AUGUST JACOB VENTZKI.
